UNITED STATES PATENT OFFICE.

JAMES W. PATTERSON, OF BRONXVILLE, NEW YORK, ASSIGNOR TO AUTO-SALES GUM AND CHOCOLATE COMPANY, OF NEW YORK, N. Y., A CORPORATION OF NEW YORK.

VENDING-MACHINE.

1,078,372.

Specification of Letters Patent.

Patented Nov. 11, 1913.

Application filed November 30, 1908. Serial No. 465,167.

To all whom it may concern:

Be it known that I, JAMES W. PATTERSON, a resident of the United States, residing at Bronxville, in the county of Westchester 5 and State of New York, have invented certain new and useful Improvements in Vending-Machines, of which the following is a specification.

My invention relates to single action coin 10 controlled vending machines. By single action I refer to that class of machines which contain but a single article, or package of articles, to be rented or sold.

The object of my invention is to produce 15 a machine of this class comprising a swinging outer casing or door consisting of front and back walls, side walls and top and bottom walls, an inner casing or receptacle consisting of a back piece, side pieces and top 20 and bottom pieces, and coin-controlled mechanism inclosed in the outer casing or door for controlling the movement thereof. The side walls of the outer casing are made to fit closely against the sides of the housing of 25 the machine. The inner casing is at its bottom pivoted to the lower end of the door or outer casing, while the latter is at its lower end hinged to the bottom of the housing.

My invention further consists in the parts 30 and combination of parts as will be herein-after more fully pointed out.

In the drawings: Figure 1 is a side elevation of a machine embodying my invention, parts being in open position. Fig. 2 is a 35 similar view with parts broken away. Fig. 3 is a front elevation, the front plate being removed. Fig. 4 is a similar view with slide cap removed. Fig. 5 is a detail view, parts being broken away to show the lock.

40 1 represents the housing provided with a suitable opening 2 for the introduction of a coin of predetermined value.

3 is an outer casing or door comprising front wall 4 and rear wall 5, and top and 45 bottom walls or pieces. Between the walls 4 and 5 I form a coin chute and position suitable controlling mechanism such, for instance, as coin mechanism. The outer casing is hinged at its lower end to the outer 50 edge of the bottom of the housing 1 as at 6.

The inner casing or receptacle 7 comprises a back piece, top and bottom pieces and two side pieces; the side pieces of the outer cas-

ing being made to fit closely against the sides of the inner casing; the bottom piece 55 of the inner casing being pivotally connected with the bottom piece of the outer casing, thereby permitting the upper end of the outer casing to swing fore and aft; the outer casing being controlled by a suitable coin 60 or other controlled mechanism.

A spring 8 is secured to the housing and bearing upon the outer casing to overcome the tendency of the door, or outer casing, and the inner casing from swinging down to 65 a horizontal position, and a spring 9 is positioned in the housing and bears on the inner casing, or the package therein, to assist the door or outer casing in swinging to open position after being released by the 70 controlling mechanism.

10 is a spring secured to the outer casing and bears on the front of the inner casing 7 to space the casing from the housing, after the outer casing has been released from its 75 controlling mechanism to facilitate the removal of the package from the casing.

The movable outer casing is provided with an inwardly projecting plate 11 having 80 an elongated slot 12 into which a pin 13, secured to the housing, projects, whereby the forward movement of the movable casing is restricted within the angle necessary to allow the removal of the package of goods.

“A” is the coin chute in alignment with 85 the entrance slot 2; “B” is the locking bar that is held in position by a spring and is intended to hold the coin after the machine has been operated until it is desired to remove it. The removal is accomplished by 90 inserting a key in the slot marked “C” thereby pushing the small lever “D”, thus retracting the locking bar and allowing the coin to drop out.

On the front wall of the outer casing 3 is 95 a slide “E” moving in ways “F” and carrying at one end lug “G” projecting into the coin chute “A”. The slide is held in normal position by a spring “H”.

Back of the coin chute and entirely separated from it by a thin plate of metal is a locking slide “I” shown by dotted lines. On its upper edge this slide carries a lug “J” and near the lower edge it has a roller “K” which projects forward through the 105 opening in the thin plate into the coin slot

and in the path of the moving coin. To the top of the housing is secured the downwardly-extending stop M arranged to be engaged by the lug J to lock the outer casing in closed position.

When a coin is dropped into the slot 2 it falls to the bottom of the upper portion of the coin chute A and lies in front of the projecting lug "G" on the slide "E". Now 10 if the slide "E" is moved to the left (as viewed in Fig. 4) the projecting lug "G" will engage with the coin and carry it along until it bears against the roller "K", and if the motion is further continued to its limit it 15 will cause the slide "I" to move carrying its lug "J" from behind the lug "A", whereupon the movable part of the box which carries the mechanism can be drawn forward and the package extracted. The box is 20 locked by closing it and inserting a key or bar in the slot "L" and pushing the slide "I" back to its first position.

While I have shown and described what I believe to be a preferred form or type of 25 construction, I do not wish to be understood as limiting the scope of my claims thereto.

In the claims I shall refer to the outer case as a door; to the casing X as a receptacle.

What I claim and desire to secure by Letters Patent is:

1. In a vending machine the combination with a housing, a door pivotally connected 35 to said housing at its bottom, and means carried by said door to control its movement, of a goods receptacle pivotally connected at its bottom to the said door.

2. In a vending machine, the combination 40 with a housing, of a door having front, side, top and bottom walls and pivotally connected to said housing at its bottom edge, means carried by said door and controlling the motion of said door, a receptacle consisting of a back piece, two side pieces, and 45 bottom piece, the bottom piece of the recep-

tacle being pivotally connected with the bottom of the door.

3. In a vending machine, the combination with a movable door consisting of front, side and top and bottom walls, of a housing consisting of a back piece, two side pieces, and top and bottom pieces, the side pieces of the door being made to fit closely against the sides of the housing, the bottom piece of 55 the door being pivotally connected with the bottom part of the housing permitting the upper end of the door to swing fore and aft, and a mechanism inclosed in the door to control the motion of the swinging door 60 substantially as described.

4. In a vending machine, the combination with a housing, of a door constructed to fit within said housing and having a hinge connection therewith, a receptacle constructed to fit snugly within said housing and having a hinge joint with said door, and a controlling means to control the movement of said door.

5. In a vending machine, the combination 70 with a housing, a door constructed to fit within said housing and having a hinge joint therewith, of a receptacle constructed to fit snugly with said housing and having a hinge joint with said door, a controlling 75 means to control the movement of said door, and means to swing the receptacle on its hinge joint relatively to the door and housing.

6. In a vending machine, the combination 80 with a housing, a door pivoted at its bottom to said housing, and mechanism to control the movement of said door, of a goods receptacle pivotally connected at its bottom with said hinged door.

In testimony whereof I affix my signature in presence of two witnesses.

JAMES W. PATTERSON.
